(57) CLAIM

The ornamental design for a transparent plant stake assembly, as shown.

DESCRIPTION

FIG. 1 is a perspective view of a transparent plant stake assembly showing our new design;

FIG. 2 is a front elevational view of the embodiment shown in FIG. 1;

FIG. 3 is a side elevational view of the embodiment shown in FIG. 1;

FIG. 4 is a top plan view of the embodiment shown in FIG. 1; and,

FIG. 5 is a bottom plan view of the embodiment shown in FIG. 1.

The breaks are shown in FIGS. 1 through 3 to indicate indeterminate length.
